His Attorney.

UNITED STATES PATENT OFFICE.

OTTO STÜRNER, OF BERLIN, GERMANY, ASSIGNOR TO GENERAL ELECTRIC COMPANY,
A CORPORATION OF NEW YORK.

LOW-CAPACITY SWITCH.

Application filed January 18, 1926, Serial No. 81,880, and in Germany January 29, 1925.

My present invention relates to switches, and more particularly to low capacity switches adapted to be employed in connection with wireless signaling systems.

5 In the operation of wireless signaling systems, it is of great importance to avoid all capacitative shunts. In receivers, for example, which employ several stages of radio and audio amplification, change-over 10 switches are required. Such switches as hitherto constructed, however, possess relatively high capacity, causing thereby output losses and undesirable coupling effects. These defects are due mainly to the fact 15 that the contact members of the switches are arranged with parallel plane surfaces.

According to my present invention, a low capacity switch is secured by the avoidance of all parallel switch contact surfaces, all 20 contact members of the switch being arranged at an angle to one another. The arrangement of the contact members at an angle of 90° is specially favorable. If this is increased still further however, and the 25 contact members of the switch are arranged in the same axial direction, i. e., at an angle of 180° the capacity between the contact members is then reduced to a minimum.

The novel features which I believe to be 30 characteristic of my invention are set forth with particularity in the appended claims. My invention itself, however, both as to its organization and method of operation will best be understood from the following specification taken in connection with the accompanying drawing in which Fig. 1 shows diagrammatically a low capacity switch with the contacts thereof arranged at the ends of 35 the switch members; Fig. 2 shows an elevation of a multi-stage switch; Fig. 3 is a 40 view partly in section and partly in elevation of the multi-stage switch shown in Fig. 2.

If the angle at which the different contact members of the switch are placed to one another is 180° the contact members coacting with one another will lie axially in the same plane. In Fig. 1 this arrangement is represented diagrammatically. In this figure *i* is one contact pin and *k* the counter contact. Contact *i* is fixed in position, while *k* is arranged to be movable axially in a guide *l*. The contact *k* is biased to open position by means of spring *m*. If counter

contact *k* is raised by turning lever *n* in the direction of the arrow, the two contact pins *i* and *k* are moved into engagement with each other. Contact pins *i* and *k* are preferably of round, cross sectional form. Furthermore, the actual contact surfaces of the pins are shaped in such a manner, for example spherically, that no parallel surfaces occur in the switch.

The device shown in Figs. 2 and 3 is a switch for three different stages, each stage 65 having five breaking or contact points. The contact pins *o* are arranged in an annular portion of a vertical casing *o'*. These pins are biased to open position by means of springs *p* and have preferably the form 70 shown in Fig. 1. The corresponding counter contact pins *q* are fixed in position in an outer, annular and concentric portion of the casing *o'*. The connection of the line to contact pins *o* is effected at contact lugs *s*, 75 while the contact pins *q* are provided with connecting lugs *rr*. As already stated the switch illustrated is a three stage switch, the five contact pins associated with stage 1 being shown in closed position, while the 80 contacts associated with stages 2 and 3 are shown in open position. Movement of the contacts is effected by means of a cam *t* which may move five of the contact pins into the closed position for the time being. 85 It is not necessary, however, that the five contact pins situated adjacent to one another shall be actuated. The arrangement may be such that, for one step, every third contact may be actuated, or if desired actuating member *t* may be arranged to simultaneously control any number of its individual switches.

In order to further reduce capacitative effects, contact lugs *r*, for the connection to 95 the movable pins, are preferably arranged so that they do not lie on the same circumference, but so that at least two adjacent contact lugs are staggered with respect to one another. The external contact lugs *r* 100 are arranged in a similar manner.

The casing is constructed of any suitable material, but preferably of a material which may be pressed into form and which has a high dielectric constant.

In order also to keep the capacity against earth as low as possible the individual switches shown in Fig. 3 are so arranged in

the casing that all the contact parts, as far as possible form an angle with the surface of the earth.

What I claim as new and desire to secure by Letters Patent of the United States, is,—

1. A wireless apparatus comprising a casing, a switch mounted thereon, said switch comprising a pair of cooperating switch members permanently arranged in alignment

10 with each other, one of said members being fixed in position and the other of said members being movable longitudinally to engage one end of said fixed member.

2. A wireless apparatus comprising a casing, a switch mounted on said casing, said switch comprising a pair of cooperating switch members permanently arranged in alignment with each other, one of said members being fixed in position and the other 20 of said members being movable longitudinally to engage one end of said fixed member, said members being provided with spherical contact surfaces.

3. A wireless apparatus comprising a casing, a plurality of switches mounted thereon each switch comprising a fixed radial outer member and an inner radial movable member adapted to cooperate therewith, and a central cam member adapted to cooperate with the 30 inner ends of said radially movable members to move them into contact with said outer members each of said contacts being provided with contact lugs.

4. A wireless apparatus comprising a casing, a plurality of radially arranged switches

thereon, each of said switches comprising a stationary member and a longitudinally movable member in alignment with said stationary member; one member of each switch having connecting means whereby said member 40 may be included in an electric circuit, the connecting means on adjacent members being arranged in staggered relation.

5. A wireless apparatus comprising a casing, a plurality of radially arranged switches 45 mounted on said casing, each of said switches including a stationary member and a longitudinally movable member in alignment with the stationary member, the members of each switch being provided with connecting means 50 whereby said members may be included in an electric circuit, the connecting means associated with the movable members being so arranged that adjacent connecting members lie on the circumference of circles which have 55 different diameters.

6. A wireless apparatus comprising a casing, having an outer and an inner annular portion, said outer portion being provided with radial recesses of varying depth, contacts mounted in said recesses, radially arranged switching members mounted on said outer annular portion and cooperating with said contacts and a plurality of switch members mounted on said inner annular portion 60 and adapted to cooperate with said first mentioned switch members.

In witness whereof, I have hereunto set my hand this 18th day of December, 1925.

OTTO STÜRNER
